7 Claims. (Cl. 179—15)

The present invention relates to a system of communication by means of electrical waves and more particularly, though not exclusively, to electrical wave communication system in which the waves are modulated by impulses whether the transmission is over metallic connections, dielectric guides, or by radio.

One of the objects of the invention is the provision of means for increasing for a given band width, the number of communications that can be transmitted simultaneously.

Another object of the invention is the provision of means for permitting satisfactory reception of a transmission modulated by impulses and independently of parasites or undesired signals which may exist at the same wave length of transmission.

A communication system which embodies the features of the present invention comprises one or more transmitters, the outputs of which are modulated by impulses and which cover one another partially or entirely, means being provided at the receiver for discriminating between the different emissions either in accordance with the difference in the duration of the impulses or in accordance with the difference in the constant amplitudes of the impulses, these two factors varying from one transmission to another.

The invention will be explained in detail with reference to the drawings in which:

Fig. 1 represents two signals having the same energy, but different durations, because the first signal has double amplitude but the second signal quadruple duration;

Fig. 2a represents a series of square impulses which are repeated at equal time intervals;

Fig. 2b represents the variations of the amplitude in function of the frequency for developing in the Fourier series two different impulses;

Fig. 3 represents three series of impulses corresponding to three different simultaneous communications;

Fig. 4 represents schematically the embodiment of the invention in a receiver for the simultaneous reception of two different communications the series of impulses of which correspond to two of the series of Fig. 3; and

Fig. 4a shows a modification of the circuit of Fig. 4 to the left of the dotted line a—a.

The invention will be described as applied to a system in which the emission is modulated by impulses in which the band width being larger, it is particularly advantageous to superimpose several communications on the carrier at the transmission and to separate them in the re-

ceiver, or to separate a desired communication from another communication or from natural or artificial parasitic disturbances.

The invention may be particularly applied to a system of transmitting a certain number of communications from one and the same point over metallic links or radio channels or to transmissions from a network of radio transmission stations, having a plurality of transmitters at different points.

In the known transmission systems employing modulation by impulses, the receivers use a threshold which in the absence of signals suppresses only the peaks of the parasitics or undesired signals so that nothing will be received. When the signals arrive, then the intensities of the desired and undesired signals may be added or subtracted. In the first case, the level will be above the threshold no matter what the intensity of the desired signals may be. In the second case, the peak of the level exceeds the threshold only if the intensity of the desired signal is greater than the intensity of the undesired signal by a potential which is just in excess of that of the threshold. In order for the peak to rise above the threshold even when the undesired signals have a maximum negative value, it is necessary that the amplitude of the desired signal exceed the sum of the potential of the negative peak and of the threshold. Since, generally speaking, the negative peak of undesired signals is equal to the positive peak which, in turn, is equal to the threshold, it follows that the desired signal must at least be greater than twice the peak of undesired signals (i. e., greater by 6 db.) whereby, if we assume that the edges of the signalling impulses are absolutely vertical, then the effect of undesired signals will be zero. However, if the intensity of the signals is not quite twice the peak of undesired signals, then the peak of the desired signal will coincide only rarely with the negative peak of undesired signals. Under these conditions, the message or the communication will in practice be only slightly mutilated.

Under certain special conditions the signal may be appreciably weaker than twice the peak of undesired signals as will be explained below.

In accordance with one embodiment of the invention, the means provided for distinguishing between two emissions (e. g. having the same strength) coming from the same point are based on the difference in the duration of impulses.

As a matter of fact, it is possible to distinguish

between signals having different duration in various ways, two of which will now be described.

Fig. 1 represents two signals, 1 and 2, having the same total energy but the duration of which have a certain predetermined relationship, in the present case 4. For a given total energy, the peak is inversely proportional to the square root of the duration. The relationship between the peaks in Fig. 1 will therefore be 2.

By considering an impulse 3 having a duration t which is repeated at intervals T , Fig. 2a, if F is the frequency having a period T and f the frequency having period t , if the series of impulses of Fig. 2a are expressed in the Fourier series, we will obtain frequencies of the form nF where n will have successively all the integral values from 1 to infinity. The curve in solid lines 4 of Fig. 2b represents approximately the manner in which the amplitude (the ordinate) of frequency nF (the abscissa) varies in function of n . It will be seen that although the amplitude has substantially a constant value until nF becomes equal to approximately $f/2$, the value of the amplitude will have peaks around frequencies $3f/2$, $5f/2$, etc. and depressions around frequencies f , $2f$, $3f$, etc.

If we deal with a single impulse which is not repeated, then T becomes infinite and the diagram of Fig. 2b continuous. If an impulse (which may be a direct current impulse on a wire or a series of periods of high frequency on a wire or by radio and the amplitude of which is like that of the impulse illustrated in Fig. 2a) has a square form at the moment of transmission, its form in the receiver will depend on the passing band of the receiver. Roughly speaking, one may admit that in order to obtain satisfactory reproduction at the receiver, a passing band of the order of f is required. If the band which is necessary for suitably receiving the long impulse 2 of Fig. 1 is f , then the band which is necessary for receiving the short impulse 1 will be $4f$. However, in the last case the amplitudes of the frequencies of the Fourier series will be substantially one-half that of the frequencies corresponding to the long impulses 2. The amplitudes will follow the dotted curve 5 in Fig. 2b. It will be seen, therefore, that if the two impulses are received in a receiver, the passing band of which is $4f$, then the peak of the short impulse 1 will be approximately twice as strong as the peak of the long impulse 2. If, on the other hand, the passing band of the receiver is f , then the amplitude of the long impulse 2 will be almost twice that of the short impulse 1.

From this standpoint, the object of the invention is to separate in the receiver the received signals having different durations of emission by suitably selecting the passing band width so as to increase the relationship of the peaks of two impulses having different duration.

If, in order to preserve in the receiver the more abrupt edges of the impulses, a band is passed which is wider than f in the assumed case for the long impulse, and which is wider than $4f$ for the short impulse, then the results will be quantitatively but not qualitatively modified.

It must be noted that by suitably selecting the passing band width, one may at will either separate the impulses of different duration by increasing the relationship between their peaks or diminish this relationship, i. e. favour a mixed reception.

A receiver arranged in accordance with this aspect of the invention will, therefore, have such

75 a passing band that it will establish the desired relationship between the peaks of impulses of different duration, and means for reproducing these impulses comprising threshold arrangements which permit the separate reproduction of the different impulses. Such arrangements are well known in themselves and will, therefore not be described in greater detail.

10 The main advantage of the invention from this standpoint is the possibility of providing a minimum band width whereby parasitics caused by other stations will be reduced to a minimum. However, it may be desirable in accordance with another aspect of the invention to provide multiple receivers having a different arrangement. Such receivers may be used no matter what may be the relative duration of the impulses in the different messages as long as the amplitude which is supposed to be constant for each series of impulses does not have the same intensity as the impulses corresponding to another message.

20 Before describing in detail the invention from this view-point, I wish to note that generally speaking the duration of an impulse is short with respect to the time elapsing between the impulses of a given communication. It happens, therefore, only rarely that two impulses of two different messages are received at the same instant.

25 Bearing this in mind, Fig. 3 represents three series of impulses, 6, 7, 8, corresponding to three different messages. After amplification, these impulses may in accordance with the present invention actuate respectively, three receivers which for convenience will be termed A, B, C. 30 The threshold of receiver A has the value 9 of Fig. 3, of receiver B, the value is 10, and of receiver C, the value is 11. The impulses received by the different receivers correspond in the case of receiver A, the impulses 6, in the case of receiver B, to impulses 6 + 7 and in the case of receiver C to 6 + 7 + 8.

35 Receiver A picks up, therefore, the message transmitted by the impulses 6 without disturbance by the other messages. The impulses thus received by A are amplified and re-introduced in the opposite sense either before or after detection into the receiver B in a manner to render the latter inoperative during the impulses. Unless an impulse 6 coincides with an impulse 7, in the output of the receiver B, we will obtain a series of impulses which are not disturbed by the messages 8 and 9.

40 In the same manner, the two receivers A and B may be arranged to render the receiver C inoperative during the impulses 6 and 7. In this manner, one will obtain only the impulses 8 in the output of receiver C. Obviously, the same arrangement may be applied to a larger number of messages at a point in the reception. In each case, the impulses in the individual receivers will actuate known receivers which will transform the series of impulses into intelligible messages.

45 A schematic representation of this embodiment of the invention is shown in Fig. 4 for only two messages in order to simplify the drawings.

In this figure, an antenna 12 collects the signals of two messages from two transmitters 12A and 12B, which are arranged to transmit signals corresponding, for instance, to the impulses 6 and 7 respectively, and after amplification in any suitable amplifier 13, these are transmitted to two receivers schematically represented at 14 and 15 in the form of a usual electronic discharge tube circuit, although obviously

these receivers may be of any other type. Each receiver 14 or 15 has its output connected to an amplifier 16 or 17 and these, in turn, to a detector 18 or 19 and the output of the detector after amplification at 20 or 21 is transmitted to an impulse demodulator 22 or 23, i. e. to an arrangement for retransforming the series of impulses into an intelligible message which can be heard in the telephone receivers 24 and 25.

The impulses of the receiver 14 must be reintroduced into the receiver 15. If these impulses are reintroduced before detection, then their intensity and phase may be regulated. This regulator, which may be of any well-known type is indicated at 26. Alternatively the impulses in the upper receiving path may be introduced into the lower receiving path after the detectors in which case the phase regulator 26 is not required.

It should be understood that the word "amplifier" as above used includes, if desired, frequency modulation amplifiers also.

An impulse 6 will from time to time coincide with an impulse 7 and will blot it out in the receiver 15, whereby a distortion will be produced in the channel of receiver 15. If the duration of the impulses is three microseconds and the frequency of the impulses 10,000 per second (impulses spaced by 100 microseconds) there will be partial blotting out once in 33, i. e. 300 times per second. However, this partial blotting out is not important and the only thing that counts is complete blotting out. Complete blotting out occurs when the two impulses coincide, the time difference being less than one period of the high frequency, i. e. at 6 meter wave $\frac{1}{50}$ microsecond. At an impulse frequency of 10,000, this will occur less than once in 5,000, i. e. twice every second.

If we have n channels, then the n th will be subjected to blotting out n times more often and the quality of its circuit will be reduced by that much.

Until now we have considered only channels in which the duration of the impulses was the same. If this duration is different in each case, then there never will be complete blotting out if the difference in the duration of the impulses is at least equal to one period of the high frequency, i. e. in the example given to $\frac{1}{50}$ of a microsecond in 3 microseconds, and if the first channel has the shortest duration. If the duration of the impulses 7 is longer than the duration of the impulses 6, then the blotting out of the receiver 15 by the impulses 6 might produce a void in the middle of each impulse 7 and thus two instead of one impulse 7 will be obtained. In order to avoid this difficulty, in accordance with the present invention, during an interval of time which is slightly longer than the duration of the impulses 6 which are introduced in the receiver 15, the arrangement for transforming the output of 15 into intelligible messages is rendered inoperative.

Fig. 4a illustrates how the difference between the amplitude peaks of two impulse modulated transmissions, the impulses of which are of different duration, may be increased by inserting pass filters 25 and 26 ahead of the limiters 14, 15, the pass bands of these filters being selected as previously explained.

In accordance with another feature of the invention, carrier frequency waves may be used which are slightly different for the different messages, although the band width in the re-

ceiver is wide enough to receive more than one message. If the band is wider than is necessary for the impulses of, e. g. two messages, just to attain their peaks in a time equal to the duration of the impulses which are assumed to be square, then according to the present invention, the relative change in phase between these two channels is utilized. As above stated, generally a difference in intensity of the order of six decibels is needed between two signals in order to separate them. This condition is imposed by the fact that the weaker signal may be in phase opposition with the stronger signal. By admitting several high-frequency oscillations by impulses, the message which it is desired to suppress must be of the same phase as the signal so that such a difference of six decibels is necessary.

Considering now the case of an impulse of three microseconds at a frequency 10 megacycles, there will be 30 oscillations per impulse. If the undesired signal to which we shall refer as the disturbance signal has a phase change of 180° , it will be added to the desired signal during the impulse, at least at right angles, and in this case, the threshold will be exceeded even when the signal is inferior to the disturbance signal provided that the latter never stops. In order to obtain a change of 180° , the frequencies must differ by $\frac{1}{50}$, i. e. by 1.7 per cent. Assuming that the threshold is slightly higher than the disturbance signal, and that the signal must generally surpass this threshold even in the absence of a disturbance, the signal must exceed the disturbance simply by a value which depends upon the duration of the impulses, on the number of impulses per second, and on the difference in the relative energy carried by the impulses, but which may be substantially lower than 6 decibels.

It should be noted that the arrangements above described are particularly applicable to radio-channel transmission in which one message is on purpose disturbed. By means of the invention it is possible to separate from the communication a disturbance unless the duration, frequency, intensity, and phase of the disturbance relative to the impulses are such that the two signals cannot be separated any more. However, it is very difficult to obtain all these characteristics whereby it may be said that a system of communication arranged in accordance with the present invention cannot in practice be disturbed by disturbances produced on purpose. If, however, unintentional disturbances were produced, then the duration of the impulses could easily be varied, e. g. in accordance with a code predetermined between transmitting and receiving stations.

In the case of a network of radio transmitting stations, the fading will generally be different for the different stations. By network, I wish to include also the above mentioned case of a desired transmitting and a disturbing station.

Although the invention has been explained as applied to waves modulated by impulses, it need not be limited to such systems, but may be applied to frequency-modulation systems also. In fact, although the image frequencies are not the same in the output of the limiters, it is possible to place in opposition the waves of undesired stations and to suppress the disturbance by certain image frequencies being less confusing than disturbance by undesired stations.

Obviously, the invention is not limited to the embodiments herein disclosed but may be modi-

filed in many ways without departing from the spirit thereof.

What is claimed is:

1. A receiving arrangement for an electric wave signalling system comprising means for simultaneously deriving from two signal transmitting channels respectively two signal wave trains of substantially constant but different amplitudes, first and second receiving paths each including a limiting device, and means located in the first path receiving said signal wave train of greater amplitude for injecting in opposition the resultant of said latter wave train into the second path receiving additionally said signal wave train of lesser amplitude, whereby in said second path the effect of said signal wave train of greater amplitude is substantially cancelled out.

2. A receiving arrangement for an electric wave signalling system comprising means for simultaneously deriving from n signal transmitting channels respectively, n signal wave trains of substantially constant but different amplitudes, n receiving paths each including a limiting device the several limiting devices each being adjusted to a different threshold point, and means including said limiting devices for discriminating between said signal wave trains in said receiving paths, said discriminating means also including means for injecting in opposition a first signal from one path receiving said first signal alone, into another path receiving said signal and a second signal, whereby in said last mentioned path the effect of said first signal is substantially cancelled out.

3. A receiving arrangement for an electric wave signalling system comprising means for simultaneously deriving from two transmitting signal channels respectively two signal wave trains of substantially constant but different amplitudes, first and second receiving paths each including a limiting device, the limiting device in said first path being adjusted to have such a threshold that it passes the peaks of both said wave trains and the limiting device in the second path being adjusted to have such a threshold that it passes the peaks of one wave train only, and means controlled by the wave train in said second path for excluding the same wave train from the output of said first path.

4. A receiving arrangement for an electric wave signalling system comprising means for simultaneously deriving from n transmitting signal channels respectively n signal wave trains of substantially constant but different amplitudes, n receiving paths each including a limiting device 55

the several limiting devices each being adjusted to a different threshold point so that a first receiving path is receptive to one signal channel wave train, a second receiving path is receptive to two signal channel wave trains, a third receiving path is receptive to three signal channel wave trains and so on, an output circuit for each receiving path, and means coupled between each said receiving path which is receptive to at least two signal channel wave trains and at least one of the other receiving paths for excluding all but one of said signal channel wave trains from the output circuits of the receiving paths which are receptive to more than one signal channel wave train.

5. A receiving arrangement according to claim 4 for simultaneously and selectively receiving a plurality of impulse modulated signal wave transmissions distinguished by different constant impulse amplitudes, wherein said means coupled between each said receiving path which is receptive to at least two signal channel wave trains and at least one of the other receiving paths includes means for introducing into each said first-mentioned receiving path wave trains which are of equal intensity and opposite phase to the wave trains which are required to be excluded from such path.

6. A receiving arrangement according to claim 30 for simultaneously and selectively receiving a plurality of impulse modulated signal wave transmissions each distinguished by a different duration of impulses constituting the signals, wherein a pass filter is included in each said receiving path at a point preceding the limiting device in the respective path, the pass bands of said filters being selected so as to increase the difference between the peaks of the impulses constituting the several signal wave transmissions.

7. An electric wave signaling system comprising means for transmitting two signals from which two signal wave trains of substantially constant but different amplitudes may be respectively derived, means to receive said signals and to derive said two signal wave trains therefrom, first and second receiving paths each including a limited device, and means located in the first path receiving said signal wave train of great amplitude for injecting in opposition the resultant of said latter wave train into the second path receiving additionally said signal wave train of lesser amplitude, whereby in said second path the effect of said signal wave train of greater amplitude is substantially cancelled out.

EDWARD HILL ULLRICH.
